CLAIM

The ornamental design for fuel cell, as shown and described.

DESCRIPTION

FIG. 1 is a top plan view of a fuel cell;
FIG. 2 is a front elevational view thereof;
FIG. 3 is a rear elevational view thereof;
FIG. 4 is a bottom plan view thereof;
FIG. 5 is a right side elevation thereof, the left side being a mirror image of that shown;
FIG. 6 is a perspective view of a fuel cell, showing my new design, the broken lines showing the fittings secured to my new design is for illustrative purposes only and forms no part of the claimed design.
